CHARLES S. PECK, OF DANBURY, CONNECTICUT, ASSIGNOR TO PECK FUR COMPANY, OF DANBURY, CONNECTICUT, A COPARTNERSHIP CONSISTING OF CHARLES S. PECK AND SIDNEY C. PECK.

FUR-SKIN-CUTTING MACHINE.

1,321,665.

Specification of Letters Patent. Patented Nov. 11, 1919.

Application filed September 3, 1918. Serial No. 252,349.

To all whom it may concern:

Be it known that I, CHARLES S. PECK, a citizen of the United States, residing at Danbury, county of Fairfield, State of Connecticut, have invented an Improvement in Fur-Skin-Cutting Machines, of which the following is a specification.

This invention relates to the class of machines used for cutting the fur from the skins of rabbits and other fur bearing animals, the fur being used principally in the manufacture of fur felt hats, and the invention has for its object to greatly improve the construction and operation of the machine, the special purposes being to avoid waste of fur, which now brings a very high price, to wholly do away with packing of the cylinder cap, which has heretofore been necessary, and to provide novel adjustments which greatly simplify and improve the operation of the machine.

It is of course well understood by those familiar with the art that the cutter cylinder in this class of machines, rotates at a high velocity, two thousand or more rotations per minute, and that the knives which project radially and spirally from the cylinder extend from one-fourth to five-eighths of an inch therefrom. The rotation of this cylinder with its knives produces a very strong draft or air current which has heretofore caused a serious loss of high grade fur which has been drawn into the machine and passed out through the suction pipe as second grade fur. This loss of high grade fur has heretofore been prevented to a certain extent by packing the interior of the cylinder cap with fur and waste. This has been effected by smearing the inner side of the cylinder cap with oil and throwing waste and fur upon it, a portion of which would adhere to the oil and thus make a more or less unsatisfactory packing which might stay in place for a day or two but more often for a short time only, repacking being necessary every time the packing comes out, and it being necessary to remove the cap and take out the cylinder for the purpose of grinding the knives, usually twice a day.

My present invention overcomes this difficulty entirely, renders packing of the cylin-

der cap unnecessary and practically eliminates the loss of high grade fur which has heretofore been unavoidable.

In the accompanying drawings forming a part of this specification, Figure 1 is a side elevation of my novel machine;

Fig. 2 a plan view on an enlarged scale, and

Fig. 3 is a vertical section thereof.

10 denotes the bed, 11 the cutter cylinder, 12 the cylinder knives, which are arranged spirally and radially relatively to the cylinder, 13 the bed knife, 14 the feed rolls, and 15 the suction pipe.

The skins to be operated upon are passed through the feed rolls fur side down and the fur is removed therefrom and the skin is cut into narrow strips through co-operation of the cylinder knives with the bed knife. The fur drops down toward the left, as seen in Fig. 3, and passes down an incline 16 and onto a traveling apron 17 by which it is removed. The strips of skin and heavy waste drop upon an incline 18 and pass out the opposite side of the machine, and the dust is removed through the suction pipe.

19 denotes the cylinder cap, the inner side of which corresponds with the curvature of the circle described by the cylinder knives and which is detachably secured to the bed. In order to compensate for the wearing away of the cylinder knives and also to prevent any air draft which might draw fur away from the fleece, so called, that is the fur removed from the skin which should all pass down incline 16, I provide the cap with an adjustable angle or gage plate 20, and with an adjustable pad or brush 21. The cylinder cap is made relatively heavy and is provided with a horizontal upper surface, indicated by 22, over which the horizontal portion of the gage plate is adapted to slide. 23 denotes way plates secured to the cap between which the gage plate slides. The gage plate is provided with ears 24 which carry adjusting screws 25, said screws rotating freely in the ears without longitudinal movement, and having threaded engagement with ears 26 on the cap. The use of two adjusting screws enables me to adjust the ends of the

gage plate independently. The lower end of the depending portion of the gage plate is beveled or concaved to correspond approximately with the curvature of the circle 5 described by the cylinder knives. This curved coöoperating portion of the gage plate is set quite close to the edges of the cylinder knives and in coöperation with the pad, presently to be described, effectually 10 prevents air currents at the point where the cutting operation takes place. The gage plate is locked in position after adjustment by a screw 27 which passes through a slot 15 in the horizontal portion of the gage plate and engages the horizontal portion of the cylinder cap.

I have shown the adjustable pad or brush as hinged to the cap plate which is a preferable construction although not essential.

20 As a means of adjustment the pad is provided near its free edge with hinged locking screws 28 which are adapted to swing into slots in ears 29 on the cylinder cap which projects over the pad. Wing nuts 30 25 on the screws engage the ears and force the pad into close engagement with the edges of the cylinder knives. The desired adjustment is retained by means of nuts 31 on the locking screws which are turned into engagement with the underside of the slotted ears, see Fig. 3 in connection with Fig. 2. The special construction of the pad is not an essential feature of the invention. In 30 practice I have used a pad formed from tufts of bristles, as shown in the drawing, and find it entirely satisfactory.

In order to insure an even and regular feeding of the skins at the center, that is midway between the ends of the bed knife 40 and the cutter cylinder, I have provided a novel adjustment of the feed roll journal bearing blocks which are indicated by 32. These bearing blocks are provided with slots 33, shown as inclined, which receive the journals of the feed rolls. One of the journals of the upper feed roll carries a belt pulley 35. The other ends of both feed roll journals carry intermeshing pinions 36 which lie outside the bearing block. 37 denotes retaining blocks which are slidable in the slots 50 in the bearing blocks, the retaining block at the pulley end being held in place by a pin 38 and the retaining block at the other end by a lever 39 which engages the outer end of the block and carries a weight 40. The bearing blocks rest upon carrying plates 41. The carrying plates are vertically adjustable in recesses 42 in the bed by means of adjusting screws 43 and are locked in 55 place after adjustment by means of screws 44 which pass through vertical slots in the carrying plates and engage the bed. The bearing blocks are adjustable on the carrying plates with relation to the cutter cylinder. I have shown as a means of adjust-

ment flattened bolts 45 which extend upward from the carrying plates and pass through slots in the bearing blocks. Nuts 46 on the bolts lock the bearing blocks in place after adjustment. It will thus be seen that I provide independent vertical adjustment and lateral adjustment for each end of the feed roll journals, which enables me to adjust the feed rolls with the required accuracy to insure an even and regular center feed of the 75 skins, that is I prevent any tendency of the skins to feed sidewise in either direction.

The bed knife is vertically adjustable and also bodily adjustable toward and from the cutting cylinder in the usual manner which 80 is clearly illustrated and is not thought to require description in detail.

I have also illustrated driving connections which I shall not describe in detail as specifically they form no part of the present invention and may moreover be greatly varied 85 without affecting the operativeness of the machine.

Having thus described my invention, I claim:

90 1. A machine of the character described, comprising a cutter cylinder, a cylinder cap having an adjustable pad, and means for adjusting the pad relatively to the cutter cylinder.

95 2. A machine of the character described, comprising a cutter cylinder, a cylinder cap, a curved pad hinged to the cap, and means for adjusting the pad relatively to the cylinder.

100 3. A machine of the character described, comprising a cutter cylinder, a cylinder cap, a brush pad forming part of the cap, and means for adjusting said pad relatively to the cylinder.

105 4. A machine of the character described, comprising a cutter cylinder, a cylinder cap, a pad hinged to the cap and provided with swinging locking screws, ears on the cap adapted to be engaged by the locking screws, 110 and nuts on the screws engaging the ears to lock the pad at any required adjustment relatively to the cylinder.

115 5. A machine of the character described, comprising a cutter cylinder, a cylinder cap having a horizontal surface, a gage plate adapted to slide over said surface and having a depending portion, and means for adjusting each end of the gage plate laterally with relation to the cutter cylinder.

120 6. A machine of the character described, comprising a cutter cylinder, a cylinder cap, a hinged pad forming a part of the cap, a gage plate carried by the cap, and means for adjusting said pad and said gage plate 125 relatively to the cutter cylinder.

125 7. In a machine of the character described the combination of a cutter cylinder, a bed knife, feed rolls, and means at each end of the feed rolls for imparting independent 130

vertical and lateral adjustments thereto with relation to the cutter cylinder, whereby center feed of the skins is insured.

8. In a machine of the character described
5 the combination of a cutter cylinder, a bed
knife, feed rolls, bearing blocks in which
the feed rolls are journaled, carrying plates

by which the bearing blocks are carried,
means for adjusting the bearing blocks laterally with relation to the cutter cylinder, 10
and means for adjusting the carrying plates vertically.

In testimony whereof I affix my signature.
CHARLES S. PECK.
